UNITED STATES PATENT OFFICE.

ALLEN B. COOKE, OF DANVILLE, ILLINOIS, ASSIGNOR TO UNITED AUTOGRAPHIC REGISTER CO., OF CHICAGO, ILLINOIS, A CORPORATION OF ILLINOIS.

AUTOGRAPHIC REGISTER.

Application filed November 10, 1924. Serial No. 748,929.

This invention relates to autographic registers and has for its principal object to provide a register of this character with means for separating and directing one or 5 more of the strips into a filing space and for cutting such strip into individual slips and also for arranging such slips in orderly fashion in the filing space for binding. According to the invention the filing space 10 of the register is provided with one or more filing pins which are movably mounted and actuated in such a manner as to be projected through the individual slips as they enter the filing space, so that the slips are engaged one after the other by the pins. Preferably the arrangement of the parts is such that the slips are stacked face downward upon the filing pins so that they may be slid off of such pins on to the pins or 20 posts of a storage binder and in doing this the backs of the slips will face toward the back of the binder.

In further describing the invention reference will be hereinafter made to the accompanying drawings which illustrate a practical means of carrying out the above mentioned object of the invention. In these drawings:—

Fig. 1 is a vertical longitudinal sectional view of a portion of an autographic register equipped with a mechanism constructed in accordance with the principles of the invention;

Fig. 2 is a transverse sectional view of the device, taken substantially on the plane indicated by the line 2—2 of Fig. 1;

Fig. 3 is a view similar to Fig. 1 showing the position of the parts shortly after the severing means has been actuated and before the filing pins have been allowed to pass into engagement with the next slip of the strip forming the record to be kept in the filing chamber;

Fig. 4 is a view somewhat similar to Fig. 3 showing the position of the parts just after the filing pins have engaged the slip;

Fig. 5 is a vertical longitudinal sectional view of a portion of the strip feeding or drawing means and illustrating particularly certain construction of the manually operated severing means and the manner in which it co-acts with the means for actuating the filing pins;

Fig. 6 is a perspective view of a portion 55 of one of the strips which is adapted to be

used in the device, this view illustrating the strip somewhat in the position in which it appears in Fig. 1; and

Fig. 7 is a detail perspective view of a portion of the filing pin actuating mechanism.

In the illustrated embodiment of the invention the numeral 1 designates the casing of an autographic register. A portion of the top of this casing is provided in the usual manner with a bearing surface or platen 2 over which several of the paper strips are to be fed or drawn and which supports the strips at the time they are written upon by the user of the device. Before proceeding with a detail description of the means for drawing the paper strips across the bearing surface and the other parts of the invention it will be explained that the strips intended to be used in the machine are preferably ruled into a series of slips so that when the slips are to be used as sale slips in a store or business establishment the salesman may fill in the name and address of the purchaser and the number and price of the articles purchased. In a device of this character it is customary to make manifold copies of the slips, so that two or more of the strips arranged in alignment are passed over the bearing surface and carbon paper or other duplicating medium is arranged between the strips so that the matter written upon the uppermost strip will be transferred to the ones beneath it. The numeral 3 indicates one of the paper strips and upon referring to Fig. 6 it will be seen how this strip is divided into a series of slips 4.

Means for drawing the strips over the bearing surface 2 consists of a roller 5 mounted above the upper side of the casing beyond the bearing surface 2 so as to bear upon the upper side of the uppermost strip. Coacting with this roller 5 is a pair of rollers 6. These rollers 6 are mounted upon a shaft 7 which extends transversely across the casing 1, so that the rollers 6 are disposed within the casing and are arranged to bear against the lower side of the lowermost strip. Each roller 6 consists of a pair of spaced disks 8, as clearly shown in Fig. 2, and the roller 5 is provided with peripheral grooves 9 opposite the spaces between each set of disks 8. One end of the shaft 7 upon which the rollers 6 are mounted ex-

tends beyond one side of the casing 1 and is provided with a crank handle 10 by which the shaft and rollers 6 and 5 constituting the paper feeding or drawing means may be 5 manually operated.

As clearly shown in Fig. 6 the strips of paper are provided adjacent the upper edges of the individual slips with pairs of perforations 11. These perforations constitute a means by which several of the strips may be arranged in alinement as well as a means by which the strips will come to rest during a slow rotation of the handle 10, for these perforations are arranged so as to pass 10 over the rollers 6 and when they come directly between the rollers 6 and the roller 5 the strips of paper will momentarily be released by the rollers and in that way the operator of the machine will be able to tell 15 just when to cease turning the handle.

Extending transversely across the upper portion of the casing 1 at a point somewhat between the rollers 5 and 6 and slightly beyond the points of contact of such rollers is 20 a separating edge 12. This is designed so as to direct certain of the strips to the outside of the casing where they may be torn off and given to the customer or otherwise disposed of, and to direct one or more of the 25 lowermost strips into the rear end of the casing which constitutes the filing chamber. This chamber is indicated by the numerical 30 13.

Also extending transversely across the 35 upper part of the casing 1 and attached to the rear end of the separating edge 12 is a rough or a sharp edge 55. This edge is immovable with respect to the casing 1 and is for the purpose of tearing or cutting the 40 strip into slips. Immediately to the rear of this edge 55 is a pair of clamps 15 and 16. Clamp 16 rotates about a pivot in frame 1 at 56 and is held against a pin 53 by spring 52. Clamp 15 is attached to arm 42 which 45 rotates about a pivot in frame 1 at 14. Arm 42 is held against pin 54 by the tension of spring 19. Mounted with 42 on pivot 14 is dog 51 which is so arranged as to be positively rotated in an anti-clockwise direction 50 by 42 but which depends upon spring 43 for its clockwise rotation. In order to manually operate 42 and thus actuate 51, 15 and 16 there is attached to 42 the handle 17. By depressing 17 arm 42 causes 15 to rise and 55 meet clamp 16 thus clamping or binding between 15 and 16 any paper that may be protruding beyond the edge 55. Continued depression of 17 will cause 15 and 16 to carry the paper with them beyond the upper 60 extremity of edge 55 and since the paper is held firmly at the point of contact between rollers 5 and 6 will cause the paper to be torn or cut off along edge 55. Upon the removal of the hand of the operator from handle 17 the action of springs 19 and 52

cause 16 and 15 respectively to return to their normal positions thus making an opening between 16 and 15 thru which the paper may be driven.

Extending transversely across the lower portion of the casing 1 at a point directly beneath the clamp 15 is a shaft 20, which carries a pair of upstanding filing pins 21. These pins 21 are located at points along the shaft so that their upper ends which are more or less pointed and curved forwardly, are positioned between the disks 8 of the roller 6. One end of the shaft 20 carries an upstanding arm 22. A coil spring 23 connected at one end to the upper portion of the arm 22 and at the other end to a bracket 24 fastened to the bottom of the casing, yieldably holds the intermediate portion of the arm in engagement with the free end of an adjusting screw 25 which is threaded through the bracket. The arm 22 is fixed to the shaft 20 the same as the pins 21, but turnably mounted upon the shaft 20 at the vicinity of the arm 22 is a lever 26. One arm 27 of this lever extends forwardly of the casing, that is, away from the filing chamber 13, and connected to the free end of this arm is the coil spring 28. This coil spring is also connected to an adjacent portion of the arm 22. A lug 29 extends from the arm 27 upwardly and rearwardly so as to be engaged at its free end by the front edge of the arm 22. The arm 30 of the lever 26 extends rearwardly in the direction of the filing chamber and is preferably beveled from its lower side. From the construction so far described it will be seen that when the arm 30 is depressed so as to rock the lever 26 the lug 29 bearing against the front side of the arm 22 will rock the arm 22, thus 70 rocking the shaft 20 and the pins 21 and causing the upper free end of the latter to be moved rearwardly away from the rollers 6.

Pivoted at its front end as at 31 to one side of the casing 1 is a substantially horizontal lever 32, to the rear end of which is pivotally connected a depending rod 33. The lower end portion of this rod 33 carries a forwardly extending lug 34, the free end of which is beveled from its upper side. As will be hereinafter explained the rod 33 is given an up and down movement and so in order to guide its lower end, the latter is arranged to slide in a guide aperture 35 in a block 36 which rests upon the bottom of the casing 1. This block 36 has a sliding adjustment with the bottom of the casing 1 by means of a screw 37 projecting through a slot 38, and the adjusting is done by means of an adjusting screw 39 which extends through a fixed block 40 mounted upon the bottom of the casing. The free end of the screw 39 is threaded and engages a threaded aperture in the block 36. It will therefore 100

be seen that turning of the screw 39 will adjust the block 36 toward or from the block 40 according to the direction in which the screw is turned. When the device is set up for use the block 36 should be adjusted so that upon a downward movement of the rod 33 the lug 34 will engage the arm 30 of the lever 26 so as to rock said lever and cause the aforesaid movement of the filing pins 21.

The aforesaid lever 17 for actuating the severing means is preferably arranged along one side of the casing 1 and carries a depending arm 42. This arm 42 upon being rotated anti-clockwise by the depression of 17 carries with it also in an anti-clockwise direction the dog 51 causing 51 to slip off of the lug 44 which extends upwardly from the arm 32. A coil spring 45 connected at one end to the upper side of the casing 1 and at its other end to the arm 32, normally holds the arm 32 raised and returns it to the raised position after being depressed.

The arm 32 is provided on one side at a point intermediate of its ends with a roller 46. This roller 46 is eccentrically mounted on the side of the arm 32 and is positioned to be engaged by a roller or disk 47 fixed upon the shaft 7.

Before proceeding with an explanation of the operation of the machine it will be explained that the clamp 15 does not extend directly or straight across the machine but is so formed as to not interfere with rollers 6 made up of disks 8. The clamp 15 is so shaped as to meet and push on the clamp 16 on as much of the length of 16 as is possible and still clear the rollers 6. It may further be explained that rollers 6 while they are preferably made out of the disks 8, they may be otherwise constructed. In order to facilitate and increase the gripping action of 15 and 16 upon the paper they are preferably provided with suitable roughened or anti-slipping gripping edges. To further facilitate the tearing or cutting of the paper across the edge 55 this edge may be shaped so that the action will be somewhat that of a shear. This may be accomplished by having edge 55 shaped somewhat as shown in Figure 2 so that the cutting or tearing will start at two points in line with the points of contact of rollers 5 and 6. This for the reason that the paper is held firmly at these points at the time the severing means is in operation. From the points in line with the points of contact of 5 and 6 the edge 55 may be bent away from the paper slightly so that the separation may be gradually continued by the continued upward motion of 15 and 16.

The machine may be used with any number of strips and they may be separated and directed to the outside of the casing or into the filing chamber as desired. In many instances, however, three strips may be used, the two uppermost being directed outside the casing and torn off by the hand of the operator and the lowermost being directed into the filing chamber and severed into 70 slips by the action of the clamps across the edge 55, and automatically stacked or filed upon the pins 21. When the machine is used for separating and directing the strips in this manner the two uppermost strips are 75 passed between the rollers 5 and 6 so as to be directed upwardly by the separating edge 12, while the lowermost strip is passed below the separating edge 12. Assuming that the three strips are arranged in alinement, 80 that is with their apertures 11 in alinement and that the three strips are positioned so that their alined apertures 11 are in the position shown in Fig. 1, that is located between the rollers 5 and 6, and also assuming 85 that a number of slips have already been stacked in the filing chamber, and that a new slip has been written out and it is desired to tear off those which are to be given to the customer or otherwise disposed of, 90 and to properly file the slips that are to be so cared for in the filing chamber, the first thing to do is to press down on the lever 17. This, as will be seen from Fig. 1, will cause 95 the clamp 15 to be moved toward the clamp 16 and upon 15 meeting 16 will grip the paper or strip. Continued pressure on 17 will overcome the tension of spring 52; and 15 and 16 will move together carrying the 100 paper across edge 55 and thus separating the strip into the slips. This slip being bent into substantially a U-shape in the filing chamber because the filing pins 21 extend thru its apertures 11, will now be permitted to flatten out and pass face down onto the stack of 105 slips.

The depression of 17 rocks arm 42 which in turn rocks dog 51 so that it slips off of lug 44 carried by arm 32. As soon as this happens the spring 45, which is pulling upwardly on arm 32, brings the roller 46 into engagement with disc 47. When the crank arm 10 is turned with the parts in this position the rollers 5 and 6 will move the strips across the bearing surface 2 and the uppermost strips will pass out of the casing while the lowermost will pass partially around the rollers 6. While this is happening the roller 46 will be rotated and since this is eccentrically mounted upon the arm 32, the latter will be depressed, rocking the lever 26 and swinging the filing pins 21 so that their free ends will pass across the free edge of the lowermost strip.

Continued rotation of the handle 10 will cause the lug 34 to snap past the arm 30 of the lever 26 at a time when the spring 23 will return the arm 22 and the pins 21 to the position so that the free ends of the pins 21 will extend into the apertures 11 of the 130

next slip as such apertures come opposite the free ends of the pins. By the time the new slips have been brought completely in place over the bearing surface 2 the roller 46 will have been returned to normal position. The oppositely beveled ends of the lugs 30 and 34 and the connection which the lever 26 had with the arm 22 will permit the rod 33 to be raised to its normal position 10 without actuating or moving the pins 21.

The spring 45 raises the arm 32 as soon as the dog 51 is moved out of the way of the lug 44, and the handle 17 which actuates 42 is released immediately after it is depressed, 15 but action of dog 51 permits the handle 17 to return to normal, also the parts controlled by 17, even though the lever 32 may be raised with the lug 44 above the lower end of 51. However as soon as the arm 32 is depressed by means of the eccentrically mounted roller 46 the lug 51 will return to normal under action of spring 43, in which position 51 will again engage lug 44 when arm 32 again returns to raised position. 20 This re-engagement of 44 against 51 disengages roller 46 from roller 47 upon the continued rotation of crank 10. In this way rod 33 makes only one downward stroke for each time 17 is depressed regardless of 25 the number of times crank 10 is turned.

From the foregoing description, taken in connection with the accompanying drawings, the construction, use, operation and advantages of the invention will be readily understood. It is obvious that the lowermost strip or strips as they pass into the filing chamber of the machine are not only severed into slips but are arranged upon 30 filing pins face downward in orderly fashion for a person having access to the interior of a filing chamber to slip the accumulated stack of slips off of the filing pins onto the pins or posts of a storage binder, and since the slips are discharged face 35 downward in the filing chamber they will pass with their backs toward the back of the storage binder as they are passed off of the filing pins of the autographic register on to the pins or posts of the storage binder.

Various changes in form, proportion, and in various features of construction may be made without departing from the spirit and principle of the invention and without sacrificing any of the advantages thereof, so 40 that it is to be understood that such may be done within the meaning and scope of the appended claims.

I claim:—

1. In an autographic register for perforated strips, the combination of a strip bearing surface, manually operated means for feeding several of the strips in alinement over said surface, a separating edge located beyond said surface to direct at least one of the strips into a filing space, manually oper-

ated means for severing the last mentioned strip into slips in said filing space, a filing pin pivotally mounted in said filing space, and means actuated by said strip feeding means and adapted to oscillate the free end of 70 said pin towards and away from said feeding means whereby to direct said pin through a perforation of each slip as it enters said filing space.

2. In an autographic register, the combination of a strip bearing surface, manually operated means for feeding several strips in alinement over said surface, a separating edge located beyond said surface to direct at least the lower strip into a filing space, 80 manually operated means located beyond said separating edge to sever the last mentioned strip into slips in said filing space, a filing pin movably mounted in said filing space, and means actuated by said strip feeding means for directing said pin through each slip of the last mentioned strip as it enters said filing space, said pin actuating means being arranged to direct said pin through the slips from the faces of the latter. 85

3. In an autographic register, the combination of a strip bearing surface, manually operated means for feeding several strips in alinement over said surface, a separating edge located beyond said surface to direct at least the lower strip into a filing space, 90 manually operated means located beyond said separating edge to sever the last mentioned strip into slips in said filing space, a filing pin movably mounted in said filing space with its free end adjacent said strip severing means, and means actuated by said strip feeding means after actuation of said strip severing means for directing said pin through each slip of the last mentioned strip 100 as it enters said filing space, said pin actuating means and said strip severing means being arranged and cooperating to turn the slips as they are severed and engaged by said pin. 105

4. In an autographic register, the combination of a strip bearing surface, manually operated means located beyond said surface for drawing several strips in alinement over said surface, said means including a roller to 115 bear upon the back of the lower strip, which strip has pin receiving apertures, a separating edge located beyond said strip drawing means to direct at least the lower strip partially around said roller and into a filing space, manually operated means located beyond said separating edge to sever the last mentioned strip into slips in said filing space, a filing pin mounted in said filing space with its free end located adjacent the 120 portion of said roller around which the last mentioned strip passes, said pin being movably mounted so that its free end will move toward and away from the periphery of said roller, and means actuated by strip draw- 125

130

ing means after actuation of said strip severing means to direct the free end of said pin through each slip of the last mentioned strip from the face thereof as it passes around said roller.

5. The structure specified in claim 4 in which the pin actuating means consists of a disk mounted upon the shaft of the roller constituting a part of the strip drawing means, a lever, a roller eccentrically mounted on said lever and arranged to engage and be turned by said disk to rock said lever, means interposed between said lever and the filing pin to rock the latter when said lever is rocked, and means interposed between the strip severing means and said lever to cause its roller to engage said disk after said strip severing means is actuated.

10. 6. In an autographic register, the combination of a strip bearing surface, manually operated means for feeding several strips of paper in alinement over said surface, a separating edge located beyond said surface to direct at least the lower strip into a filing

space, a filing pin mounted in the filing 25 space upon which the slips severed from the last mentioned strip are filed, means for actuating the filing pin, a blade located beyond said separating edge for severing the last mentioned strip into slips, and means operable to grip the strip and move the same 30 across the blade.

7. In an autographic register, the combination of a strip bearing surface, means for feeding several superimposed strips over said 35 surface, a separating edge located beyond said surface to direct at least one of said strips into a filing space, means for severing the last mentioned strip into slips, said strip having pin receiving apertures, and a filing pin pivotally mounted in the filing space, and means for oscillating said pin to cause the same to project through and hold said 40 slips.

15. In testimony whereof I have hereunto, 45 affixed my signature.

ALLEN B. COOKE.
